UNITED STATES PATENT OFFICE.

JASPER DERRY, OF MEDFORD, MASSACHUSETTS, ASSIGNOR TO ANDREW TERKELSEN,
OF BOSTON, MASSACHUSETTS.

WORK SUPPORTING AND ROTATING MEANS FOR WRAPPING MACHINES.

Application filed May 11, 1925. Serial No. 29,348.

This invention relates to wrapping machines of the general type shown and described in an application for Letters Patent of George W. Prouty, Serial No. 479,410, filed June 21, 1921 adapted primarily for wrapping annular objects such, for example, as automobile tires, coils of wire, etc.

The present invention has for its object to provide a wrapping machine of this character, and more particularly a machine for wrapping automobile tires with paper having improved mechanism for supporting and rotating the tire during the wrapping operation. The improved mechanism constituting the subject matter of the present invention comprises improved supporting and driving rollers including the mountings for the rollers and the novel means by which the rollers are rotated in unison. Due to the novel arrangement and construction of my supporting and rotating rollers, the said rollers will rotate tires of different sizes through the shuttle at the same rate of speed.

The invention will be fully understood from the following description when taken in connection with the accompanying drawings and the novel features thereof will be pointed out and clearly defined in the claims at the close of this specification.

30 In said drawings:

Fig. 1 is a front elevation of a tire wrapping machine embodying my invention.

Fig. 2 is a side elevation of the machine looking from the left in Fig. 1 and showing the mountings for both pairs of supporting and rotating rollers.

Fig. 3 is an enlarged front elevation partly in section of my improved supporting and rotating rollers including their mountings and operating mechanism.

Fig. 4 is a sectional view of one pair of the supporting and rotating rollers and their driving pinion all of which are shown out of engagement so as to clearly illustrate the construction thereof.

The frame of the machine comprises a base 15 and a yoke 16 which is pivotally mounted on a shaft 17 journalled in an upright 18 rising from the base 15. The yoke 16 is provided with guide rollers 19 for the shuttle 20 which is rotated by a driving member in the form of a friction disk 21, secured to the shaft 17 and driven through connections hereinafter described, under the

control of a starting treadle 22 and an electric motor 23 supported on the base 15. The tire W to be wrapped is held by a weighted roller 14 upon the two pairs of supporting and rotating rollers 24 which are arranged on opposite sides of the shuttle 20 and are driven through a connection generally indicated at 25 from the motor 23, the arrangement being such that the tire W will be turned relatively slowly with respect to the speed of rotation of the shuttle 20. The shuttle 20 is an open shuttle, a portion of the same being cut away to provide an opening through which the tire W may be inserted. The yoke 16 may be adjusted about the fixed axis of the shaft 17 to centre the shuttle 20 with respect to tires of different sizes, said yoke being counterbalanced by a spring 27 and being located in adjusted position by means of a clamp 28 carried by an upright 29 rising from the base 15.

The wrapping material is preferably in the form of a continuous strip S of paper and is supplied from a roll 30 supported by a reel or spindle 31 carried by the yoke 16. Said paper passes from the roll 30 to any suitable tension device not shown, thence through a folding device generally indicated at 33 and thence over a guide plate 34 to the shuttle 20. The shuttle 20 comprises an annulus having on one face a circular series 35 of rollers about which the strip S is wrapped when the shuttle is rotated, said strip being fed from the shuttle about a roller 36 to the tire W. Between the shuttle 20 and the source of supply, there is provided a cutting mechanism comprising a knife 37 cooperating with a portion of the guard plate 34 to sever the strip S when a sufficient length thereof has been wound around the shuttle rollers 35 to complete the wrapping 38 of the tire W. The knife 37 is automatically actuated after a predetermined number of rotations of the driving disk 21 by a counting mechanism 38 actuated at each rotation of the driving disk by a cam projection 39 thereon, said counting mechanism being manually adjustable in accordance with the size of the articles wrapped. The above described cutting mechanism for the paper web forms no part of the present invention 105 it being understood that the roll of wrapping material may be mounted on the shuttle and no cutting mechanism used.

In accordance with the present invention the supporting and driving rollers 24 are located in pairs on opposite sides of the shuttle 20. As shown in Fig. 2, the pair of supporting rollers 24 to the left in this figure are mounted on a standard 40 which extends at an angle above the base 15 the said standard leaning toward the shuttle 20. The right hand pair of rollers 24 are carried on the vertical standard 41 also mounted on the base 15. The tire W is supported on the two pairs of rollers 24 on opposite sides of the shuttle and is rotated through the eye of the shuttle in the direction of the arrow in Fig. 2.

The rollers 24 of each pair are supported on stub shafts 42, the shafts 42 being secured at their upper ends in the end members 43 at the upper ends of the outwardly flaring extensions of the supporting standards 40 and 41. The said shafts are secured against rotation by any convenient means such as the pins 60. Each of the shafts 42 is provided at its opposite end with a tapped 25 opening to receive a stud 44, the head 45 of which retains the roller in adjustable position on the said shaft.

As clearly appears from Figs. 3 and 4, the rollers 42 are provided with extensions on the lower end faces thereof in the form of bevel gears 61. The teeth 62 of the bevel gear 61 on the roller 24 to the left in Figs. 3 and 4 extend throughout the entire face of the gear while the teeth 63 on the roller 24 to the right in these figures extend throughout only approximately half of the bevel face of the gear, the length of the teeth being approximately half of that of the teeth on the left hand roller 24, and located on the face of the gear nearest the centre of the roller. The rollers 24 are adjusted on their supporting member 40 and 41 so that the teeth of the bevel gears are maintained in proper mesh. The gear 61 on the left hand roller is driven by the bevel gear 52 on the upper end of the shaft 46 journalled in the cross members 47 and 48 of the supporting brackets 40 and 41. The bevel gear 52 is of the same size as the bevel gears 61 on the end faces of the rollers 24 and as in the case of the bevel gear on the right hand roller 24 has gear teeth which are only approximately half the length of the teeth on the bevel gear 61 of the left-hand roller 24. The teeth on the gear 52 extend from the outer edge of the gear to a point approximately at the centre of the gear face instead of from the centre to the inner edge as in the case of the gear on the right-hand roller 24. By this construction, it will be seen that the short teeth on the gear 52 drive the bevel gear 61 on the left-hand rollers 24 and the teeth on the gear 61 of the said roller being of full length drive the short teeth of the gear 61 on the right-hand roller 24. The

half length teeth on both the right-hand roller 24 and the driving gear 52, being on opposite sides of their respective gear faces, clear each other. This construction permits the triangular driving arrangement of the three bevel gears enabling the inclined rollers 42 to be positively driven in unison by a single driving gear. It will be understood that the foregoing description of the rollers 24 on the right-hand side of the shuttle 75 applies equally to the other pair of rollers 24, the supporting bracket 41 of the right-hand pair of rollers being provided with a like driving shaft 46 having a like pinion 52 on its upper end. Each of the shafts 46 are driven through bevel gears 49 secured to their lower ends which mesh with bevel gears 50 on the transverse shafts 51 and 54 journalled in the standards 40 and 41 respectively. The driving shaft 54 is connected to the motor 23 through the connections generally indicated as 25. The shaft 51 carries a sprocket 53 and the shaft 54 is provided with a like sprocket 55. A chain 56 connects the sprockets 53 and 55 so that both pairs of rollers 24 are driven at the same rate of speed from the motor 23.

From the above described construction and arrangement of the supporting and rotating mechanism, it will readily be seen that the surface speed of the entire peripheral surfaces of each of the rollers 24 is the same. It is therefore clear that tires of different sizes having different cross sectional areas will be rotated at the same rate of speed through the eye of the shuttle irrespective of the points at which they engage with the said surfaces of these rollers. Thus a small tire which will pass farther down in the V-shaped recess between the rollers will be driven at the same speed as a large tire which will rest on the roller surfaces at points farther out. This construction is a distinct improvement over the old type of supporting mechanism in which the tires were supported on one roller on each side of the shuttle. These rollers were provided with outwardly extending flanges the surface speed of which would be different at the points of engagement on the said flanges of tires of different sizes.

As clearly appears from Fig. 2 and as referred to above, the standard 40 which carries the left-hand pair of supporting rollers 24 is inclined inwardly from the base 15 toward the shuttle 20 while the standard 41 which carries the other rollers 24 is vertical with respect to the said base 15. By this arrangement of the standards 40 and 41 both pairs of rollers 24 are caused to engage the tire so as to tend to drive the body of the tire into the V-shaped recesses formed between each pair of rollers 24. The tire W being rotated in the direction of the arrow in Fig. 2, the feeding-in side is that at the

left in Fig. 2. To draw the tire in from the left and feed it through the shuttle 20 all four rollers 24 of both pairs are driven clockwise, being the direction of the arrows

5 in Fig. 2. It will be readily understood that when any pair of rollers, such as the rollers 24, which are inclined with respect to each other and have their axis in the same plane are driven together and in the same direction, any object which is brought in contact with either or both of the rollers will either be drawn by the rollers into the V-shape recess between them or will be forced to climb out of this recess, depending on which side 10 of the common plane of the axes of the rollers the object engages the roller surfaces, and further depending on their direction of rotation. This can best be illustrated by reference to Fig. 2 in which the rollers 24 are rotated in a clockwise direction. In this instance the tire engages both pairs of rollers at points on their surfaces to the left of the planes $a-a$ of their axes. To cause the tire to engage the left hand pair of rollers 24 in this manner, i. e., to the left of the plane of their axes, it is necessary to incline the rollers toward the shuttle. This has been done in the machine shown by inclining the bracket 40 as described but it is apparent 25 that the position of the rollers themselves may be changed without inclining the bracket.

It has been found sufficient for practical purposes in order to overcome enough of the 30 tendency of the left-hand rollers 24 to force the tire out of the V-shaped recess to incline the said rollers a lesser amount than that shown in Fig. 2. For example, the tire will feed satisfactorily without climbing out of the V-shaped recess if the plane of the axes 35 of the rollers 24 passes through the points of engagement of the tire with the rollers or even if the said plane is slightly to the left of the said points of engagement. The 40 satisfactory operation which results when the said plane is slightly to the left of the points of engagement is perhaps due to the weight of the tire, the weighted roller 14 and to the drawing power of the right-hand 45 rollers 24 all of which tend to hold the tire in the said recess.

It will be apparent that each degree of inclination of the left-hand rollers 24 to the right of the vertical reduces the tendency of the tire to climb out of the V-shape recess but unless the inclination is as great as that described above auxiliary guiding means will be necessary to maintain the tire in driving position on the rollers.

50 It will be understood that I do not limit myself to the particular arrangement and application of the invention described and shown, the same having been chosen for illustrative purposes merely, and that the 55 said invention, as defined by the claims here-

unto appended may be otherwise embodied and used without departure from its spirit and scope.

Having thus described my invention, I claim:

1. In a wrapping machine for annular articles in combination, an annular shuttle provided with means for wrapping a strip of wrapping material about the work passed therethrough and means for supporting annular articles of different sizes in upright position and rotating the same through said shuttle at the same rate of speed, said supporting and rotating means engaging the work at a plurality of points at opposite 75 sides of the median line of its periphery.

2. In a tire wrapping machine, in combination, an annular shuttle provided with means for wrapping a strip of wrapping material about the work passed therethrough 80 and means engaging the tire at a plurality of points at opposite sides of the median line of the tread for supporting tires of different sizes in upright position and rotating the same through said shuttle at the same rate 85 of speed.

3. Work supporting and rotating means for wrapping machines comprising a pair of rollers having angularly disposed axes intersecting in a plane perpendicular to the 90 axis of the work and passing through the work, and means for rotating said rollers in unison.

4. In a wrapping machine for annular articles, in combination, an annular shuttle provided with means for wrapping a strip of wrapping material about the work passed therethrough and means for supporting the work and moving the same through said shuttle, said last named means comprising 100 two pairs of rollers on opposite sides of said shuttle, the rollers of each pair being oppositely and upwardly inclined and means for rotating the rollers together in the same 105 direction.

5. Work supporting and rotating means for wrapping machines comprising a pair of substantially cylindrical rollers having angularly disposed axes intersecting in a plane perpendicular to the axis of the work and passing through the work and means for 110 rotating said rollers in unison.

6. Work supporting and rotating means for wrapping machines comprising a pair of substantially cylindrical rollers having angularly disposed intersecting axes, intermeshing bevel gears carried by said rollers 120 respectively, and a third bevel gear meshing with one of said first named gears to drive the same.

7. Work supporting and rotating means for wrapping machines comprising a pair of substantially cylindrical rollers having angularly disposed intersecting axes, intermeshing bevel gears carried by said rollers 125 130

respectively, and a third bevel gear meshing with one of said first named gears to drive the same, the other of said first named gears and said third gear being cut away at different points to clear one another.

8. Work supporting and rotating means for wrapping machines comprising a pair of interconnected substantially cylindrical rollers the axes of which are angularly disposed and lie in a common plane, and forming a V-shaped recess between the said rollers.

9. In a wrapping machine for annular articles, in combination, an annular shuttle and two pairs of interconnected rollers on opposite sides of said shuttle, the axes of each pair being angularly disposed and lying in a common plane providing a V-shaped recess therebetween to receive the article to be wrapped and support and rotate the same.

10. In a wrapping machine for annular articles, means for supporting the article to be wrapped in upright position and for rotating the same comprising oppositely and upwardly inclined rollers the axes of which lie in a common plane providing a V-shaped carriage to receive the article to be wrapped.

11. In a wrapping machine, in combination, an annular shuttle provided with means for wrapping a strip of wrapping material about the work passed therethrough, and means for supporting and moving the work through said shuttle, comprising a pair of rollers having angularly disposed axes, lying in a common plane, the plane of the axes of said rollers being inclined toward said shuttle.

12. In a wrapping machine for annular articles, in combination, an annular shuttle provided with means for wrapping a strip of wrapping material about the work passed therethrough and means for supporting the work and moving the same through said shuttle, said last named means comprising a pair of oppositely and upwardly

inclined rollers the axes of which lie in a common plane providing a V-shaped recess between the said rollers and means for rotating the rollers together in the same direction the said rollers being so positioned that the work engages therewith at points on the rollers on that side of the common plane of their axes from which said work approaches the said V-shaped recess.

13. In a wrapping machine for annular articles, in combination, an annular shuttle provided with means for wrapping a strip of wrapping material about the work passed therethrough and means for supporting the work and moving the same through said shuttle, said last named means comprising two pairs of rollers on opposite sides of said shuttle, the rollers of each pair being oppositely and upwardly inclined and having their axes in a common plane providing a V-shaped recess between the said rollers, and means for rotating said rollers together in the same direction, the said rollers being positioned on the machine so that the work engages the rollers of each pair at points on that side of the common plane of their axes from which said work approaches the said V-shaped recess.

14. In a machine for wrapping annular articles, means for supporting an article in upright position and rotating the same comprising a pair of oppositely and upwardly inclined rollers and means for rotating said rollers in unison.

15. In a machine for wrapping annular articles, means for supporting an article in upright position comprising a pair of rollers having intersecting axes upwardly and oppositely inclined with respect to the plane of the article supported, and means for rotating said rollers in unison and thereby rotating said article.

In testimony whereof I affix my signature.

JASPER DERRY.
